UNITED STATES PATENT OFFICE

ALBERT UPTON, OF PATERSON, NEW JERSEY, ASSIGNOR TO VAN RAALTE COMPANY, OF NEW YORK, N. Y., A CORPORATION OF NEW YORK

DESIGN FOR LACE

Application filed March 4, 1932. Serial No. 43,072. Term of patent 3½ years.

To all whom it may concern:

Be it known that I, ALBERT UPTON, a subject of Great Britain, residing in the city of Paterson, county of Passaic, and State of New Jersey, have invented a new, original, and ornamental Design for Lace, of which the following is a specification, reference being had to the accompanying drawing, forming a part thereof.

The drawing shows a perspective view of my new design for lace.

I claim:

The ornamental design for lace substantially as shown.

ALBERT UPTON.
